INVENTOR
ANDREAS NIELSEN

By Victor J. Evans
Attorney.

UNITED STATES PATENT OFFICE.

ANDREAS NIELSEN, OF SAN JUAN BAUTISTA, CALIFORNIA.

FOLDING FLOAT.

Application filed June 19, 1922. Serial No. 569,413.

To all whom it may concern:

Be it known that I, ANDREAS NIELSEN, a subject of the King of Denmark, residing at San Juan Bautista, in the county of San Benito and State of California, have invented new and useful Improvements in Folding Floats, of which the following is a specification.

This invention relates to improvements in folding floats, the principal object of which is to provide a float which may be folded in a compact space for the purpose of transportation and may be later opened and inflated for use.

Another object is to provide a cheap float which may be employed as a boat or as an amusement device.

Another object is to provide for the rigidity of the float after the same has been inflated.

Other objects and advantages will be apparent during the course of the following description.

In the accompanying drawings forming a part of this specification, and in which like numerals are employed to designate like parts throughout the same,

Figure 1 is a side elevation of my device inflated and in use,

Figure 2 is a top plan view of Figure 1 with the masts and awning removed,

Figure 3 is a cross-section taken on the line 3—3 of Figure 1,

Figure 4 is a fragmentary detail view of the folding brace,

Figure 5 is a side elevation of the float deflated and showing in dotted lines the manner of folding the sections,

Figure 6 is a view similar to Figure 5 showing the end sections folded in the manner of folding the device as a whole,

Figure 7 is a side elevation of the device entirely folded, and

Figure 8 is an end elevation of the device entirely folded.

Applicant is aware of the fact that floats have been employed for amusement purposes at the shore resorts. These floats, however, are bulky and consequently cannot be easily transported. Applicant has therefore devised means whereby a float may be constructed in such a manner that the same may be folded in a very compact space thereby allowing for transportation from one point to another.

In the accompanying drawings wherein

for the purpose of illustration is shown a preferred embodiment of my invention, the numerals 9 and 11 designate end sections, while the numerals 12 and 13 represent central sections. These sections are hinged together as shown at 14, 16 and 17. It will be noted by viewing Figure 1, that the central sections are rectangular in shape while the end sections are pointed to simulate the outline of a boat. It will also be noted that these sections are all constructed in a similar manner, therefore, the manner of constructing but one of the sections will be given.

By now referring to Figure 3, it will be noted that the deck or upper surface of the section 12 comprises a deck 18, preferably constructed of metal and having overturned flanges 19 and 21. A bottom 22 having a similar contour is provided, which bottom 75 has overturned flanges 23 and 24. The overturned flanges of the deck 18 are adapted to receive therein a block as shown at 26 and 27, while similar blocks 28 and 29 are provided in the overturned flanges 23 and 24 80 of the bottom 22. Suitable cross braces as shown at 31 and 32 are provided for the deck and bottom of the float. These cross braces are shown in dotted lines in Figure 2.

The numeral 33 designates a flexible web 85 such as canvas which has been treated with an impervious paint or similar composition. This web is wrapped about the blocks 26, 27, 28 and 29 as is best shown in Figure 3. Suitable pins 34, 36, 37 and 38 serve to secure these blocks in place and prevent withdrawal of the same from their respective positions.

Hingedly supported beneath the sections 12 and 13 of the float are hinged keels designated by the numerals 39 and 41. These keels are hinged as shown at 42 and 43 to the lower extremity of the pins 37 and 38. In order to prevent these keels from swinging while in use, I provide braces 44 and 46, 100 which braces are of the usual construction and need no further reference.

At 47, I have shown a valve through which air is admitted to the interior of the float section, which valve is of any well known 105 form. In order to prevent collapse of the deck with respect to the bottom, I provide a series of folding braces, one of which is best shown in Figure 4 and is designated by the numeral 48. This brace is pivoted to the deck as shown at 49 and is adapted to engage a pin 51 mounted upon the base. As

before mentioned, the sections thus constructed are hinged together, the hinge 16 being secured to the adjacent bottoms of the central sections 12 and 13, and in order to prevent movement of this hinge while in use, I provide latches 52 and 53. (See Figure 2).

The operation of my device is as follows:—

10 Assuming that the parts are brought to the point where the float is to be used and are removed from their canvas case, the same will appear as shown in Figures 7 and 8. The sections are then swung so as to 15 assume the position shown in Figure 6, after which the end sections are swung to the position shown in Figure 5. I now attach a pump to each of the valves 47 to inflate each section, after which I swing each of the 20 braces from their dotted line position in Figure 4 to their full line position, after which I may place, if desired, masts in each of the end sections and stretch an awning therebetween. If desired, a folding back 25 rest 54 may also be provided.

It will thus be seen that I have constructed a very simple float which may be readily manufactured, transported and used, and

one which will come within the means of the average person.

30

It is to be understood that the form of my invention herewith shown and described is to be taken as a preferred example of the same, and that various changes in the shape, size and arrangement of parts may be resorted to without departing from the spirit of the invention or the scope of the subjoined claim.

35

Having thus described my invention, I claim:—

40

In a device of the character described, a series of collapsible floats comprising sections having a rigid deck and bottom, a flexible web extending between and secured to said deck and said bottom at the ends and 45 sides, pivotal means for maintaining said deck and said bottom in spaced relation to each other, means for injecting air into the interior of said float sections formed by said deck, said bottom and said web, and keel 50 sections hinged to the opposite sides of said float sections, said keel sections being braced when open against swinging on their respective hinges.

50

In testimony whereof I affix my signature. 55
ANDREAS NIELSEN.
